UNITED STATES PATENT OFFICE.

RANDOLPH N. WILKINSON, OF HUNTINGTON, WEST VIRGINIA.

DESIGN FOR A CHILD'S VEHICLE.

52,154.

Specification for Design.

Patented July 2, 1918.

Application filed August 9, 1917. Serial No. 185,367. Term of patent 7 years.

To all whom it may concern:

Be it known that I, RANDOLPH N. WILKINSON, a citizen of the United States, residing at Huntington, in the county of Cabell and State of West Virginia, have invented a new, original, and ornamental Design for a Child's Vehicle, of which the following is a specification, reference being had to the accompanying drawing, forming part thereof.

Figure 1 is a side elevation of a child's vehicle, showing my new design.

Fig. 2 is a plan view thereof.

Fig. 3 is a front elevation.

I claim:—

The ornamental design for a child's vehicle, as shown.

RANDOLPH N. WILKINSON.

Witnesses:

T. L. MORRIS,

K. C. BEACH.
